CLAIM

The ornamental design for a flashlight, as shown and described.

DESCRIPTION

FIG. 1 is a top view of a flashlight showing our new design;
FIG. 2 is a bottom view of the flashlight of FIG. 1;
FIG. 3 is a left side view of the flashlight of FIG. 1;
FIG. 4 is a right side view thereof;
FIG. 5 is a front view thereof;
FIG. 6 is a rear view thereof;
FIG. 7 is a rear perspective view featuring the right, rear and bottom sides of the design;
FIG. 8 is a front perspective view featuring the left, front and top sides of the design;
FIG. 9 is a top view of a flashlight showing our new design with a battery affixed thereto;
FIG. 10 is a bottom view of the flashlight of FIG. 9 with the battery affixed thereto;
FIG. 11 is a left side view of the flashlight of FIG. 9;
FIG. 12 is a right side view thereof;
FIG. 13 is a front view thereof;
FIG. 14 is a rear view thereof;
FIG. 15 is a rear perspective view featuring the right, rear and bottom sides of the design; and,
FIG. 16 is a front perspective view featuring the left, front and top sides of the design.
The broken lines showings in the drawings represent unclaimed portions of the article and form no portion of the claimed design.
